UNITED STATES PATENT OFFICE.

ALBERT P. HART, OF SANTA ANA, CALIFORNIA.

PAPER-FEEDING MECHANISM FOR PRINTING PRESSES.

Application filed March 9, 1922. Serial No. 542,266.

To all whom it may concern:

Be it known that I, ALBERT P. HART, a citizen of the United States, residing at Santa Ana, in the county of Orange and State of California, have invented new and useful Improvements in Paper-Feeding Mechanism for Printing Presses, of which the following is a specification.

My invention relates to paper feeding mechanism for printing presses, particularly of the Miller type, wherein vertically movable lifting heads are provided for elevating sheets of paper to a point from which they are conveyed to the press.

In feeding mechanism of this type, the feeding of sheets of paper singly is not at all times insured, because of the tendency of the sheets to adhere to one another, which results in the lifting and conveying to the press of two or more sheets at a time.

It is the purpose of my invention to overcome this objection and the resulting disadvantages by providing an attachment for paper feeding mechanisms which is operated by the mechanism to effect the loosening of each sheet from an adjacent sheet prior to the lifting operation of the lifting heads, so that the elevation of only a single sheet of paper at a time will at all times be insured.

Although I will describe only one form of attachment embodying my invention and point out the novel features thereof in claims, it is to be understood that various changes and modifications may be made herein without departing from the spirit and scope of such claims.

In the accompanying drawings.

Figure 1 is a view showing in front elevation certain portions of a paper feeding mechanism of the Miller type having applied thereto one form of attachment embodying my invention;

Figures 2 and 3 are sectional views taken on the line 2-2 of Figure 1, showing the loosening foot of the attachment in active and inactive positions, respectively;

Figure 4 is a detail perspective view of the loosening foot and supporting arm embodied in the attachment shown in the preceding views.

Referring specifically to the drawings, in which similar parts are designated by similar reference characters, the paper feeding mechanism here shown comprises a table T,

upon which the sheets of paper adapted to be fed to the press are supported, and sustained on the table is a frame designated F which includes a bar B spanning and connecting the sides of the frame. Lifting heads H are formed on the lower ends of rods R, and these rods are mounted for vertical sliding movement within sleeves S, with which latter mechanism is associated for effecting a reciprocating movement of the rods to lower and elevate the several heads into and out of contact with the sheets of paper supported upon the table T.

The heads H are of the suction type, and flexible pipes P are connected with the heads through which a vacuum is created within the heads for causing the sheets of paper to adhere to the latter, as will be clearly understood. A hollow bar C rigidly connects all of the heads H, so that their vertical movement is simultaneous with respect to one another.

The attachment forming the subject matter or my invention comprises in the present instance a yoke 15 so formed as to embrace the bar C and to be securely held thereon by means of a clamping screw 16 which is threadedly fitted in one portion of the yoke so as to be adjustable to engage or disengage the bar in clamping or releasing the yoke, as will be understood. An arm 17 is formed integral with the yoke 15, and this arm is of L-shaped form, with its vertical portion extending above the bar C and forming a mounting for a bell crank 90

lever 18. As plainly shown in Figure 2, the lever 18 is fulcrumed at the point indicated at 19, with one arm thereof extended into a socket member 20 and retained therein by means of a screw 21. The screw 21 is also designed for the purpose of determining the lowermost position of the lever 18 by engaging with the intermediate head H, and to lock the screw in any desired position, a lock nut 22 is mounted on the shank 100 of the screw for engagement with the socket 20. The socket 20 is formed with suitable openings to removably receive the arms of a spring wire support 23, these arms normally tending to expand so that when contracted and inserted within the socket they

serve to securely retain the support against displacement from the socket. The lower end of the support 23 carries a loosening foot 24, which is preferably formed of rub- 110

ber or any other suitable material which will secure the necessary gripping action with respect to the sheets of paper.

The lever 18 is adapted to be rocked during the movement of the heads H by a coiled contractile spring 25 connected at its lower end to the lever and at its upper end to a screw 26 threadedly fitted in a bracket 27. The bracket 27 is constructed to embrace the bar B and to be securely held thereon by means of the screw 26. An extension 28 is formed in the upper end of the lever 18, and this extension is designed to cooperate with a stop member 29 for defining the position of the lever when the heads H are in their uppermost positions.

In the operation of the paper feeder, the several heads H are moved from the lower positions shown in Figure 2 to the upper positions shown in Figure 3, and during this movement a suction is created within the heads which serves to cause a sheet of paper to be lifted from the table for subsequent conveyance to the press. The suction within the heads H is only momentary or sufficiently long to elevate the paper to the desired point, and until the conveying mechanism operates to remove the paper from the heads for delivery to the press.

30 With the heads H in their uppermost position as shown in Figure 3, the extension 28 is in engagement with the stop member 29; so that the lower arm of the lever 18 is depressed substantially in a horizontal plane.

35 As the head moves downwardly, carrying with it the lever 18, the spring 25 is expanded, thereby causing the lever to swing in a clockwise direction, as when viewed from Figure 2, causing the lowering of the loosening foot 24 until it actually contacts with the uppermost sheet of the pile of paper contained on the table T. As previously described, the lowermost position of the lever is defined by the adjustment of the screw 21, 45 and it will be understood that the screw is so adjusted that in the lowermost position of the lever the foot 24 will have a substantially firm engagement with the uppermost sheet of paper. However, prior to this final

50 lowermost position of the foot, it actually contacts with the uppermost sheet of paper before the heads H reach their lowermost position, so that the foot exerts an upward pressure on the lever to swing the latter for a short distance in a clockwise direction. It is during this movement of the lever that the foot 24 is moved outwardly from the heads and over the uppermost sheet of paper, thereby loosening the latter from the

55 adjacent sheet and causing it to slightly buckle, as indicated in Figure 2. Consequently, when a suction is created within the heads H to grip the uppermost sheet of paper, this operation will be accomplished 60 without the next sheet adhering thereto, so

that the lifting of a single sheet of paper is at all times insured.

I claim as my invention:

1. In combination, a paper feeding mechanism including a paper supporting table, a stationary member, a movable member adapted to engage and disengage the paper supported on the table, lifting heads carried by the movable member, a lever sustained for rocking movement on the movable member, means connected to said lever and to the stationary member for effecting movement of the lever about its own axis when the movable member is moved, and a loosening member carried by the lever and adapted to engage the paper on said table during the movement of the movable member toward the paper whereby when the movable member is in actual engagement with the paper, the loosening member will be moved to effect the loosening of the uppermost sheet of paper.

2. In combination, a paper feeding mechanism for presses including a paper sheet supporting table and movable lifting members, a foot, a member supporting said foot and associated with the members to be rocked in one direction by the engagement of said foot with the paper on said table, such movement being in advance of the engagement of the lifting members with the paper whereby said foot is caused to move parallel with the table for effecting a loosening of the uppermost sheet.

3. In combination, a paper feeding mechanism including a stationary bar, a movable bar, lifting heads carried by the movable bar, a lever sustained for rocking movement on the movable bar, a contractile spring connected to said lever and to the stationary bar for effecting movement of the lever about its own axis when the movable bar is moved, a loosening foot carried by the lever, a screw adjustable to define the movement of said lever in one direction, and a stop member associated with the stationary bar for defining the movement of the lever in the other direction.

4. An attachment of the character described comprising a yoke, a lever pivoted on the yoke, a socket receiving one end of the lever, a screw extending through said socket and lever and adjustable therein, a spring support removably associated with the socket, a loosening foot carried by the support, an extension formed on the lever, a bracket adapted to be sustained independently of the lever, a spring connecting the lever with said bracket, and a stop member mounted on the bracket and adapted to be engaged by said extension.

5. In combination, a paper feeding mechanism including a stationary member, a movable member, lifting heads carried by the movable member, a lever sustained for

- rocking movement on the movable member, resilient means connected to said lever and to the stationary member for effecting movement of the lever about its own axis when the movable member is moved, a loosening member carried by the lever, a member adjustable to define the movement of said lever in one direction, and a stop member associated with the stationary member for defining the movement of the lever in the other direction. 5
6. An attachment of the character described, comprising a yoke, a lever pivoted on the yoke, a socket receiving one end of the lever, a member extending through said socket and lever and adjustable therein, a support removably associated with the socket, a loosening member carried by the support, an extension formed on the lever, 10
- 15
- a bracket adapted to be sustained independently of the lever, a resilient member connecting the member with said bracket, and a stop member mounted on the bracket and adapted to be engaged by said extension. 20
7. An attachment of the character described, comprising a lever adapted to be sustained for locking movement on a movable member, resilient means adapted to effect movement of the lever upon movement of the movable member, a loosening foot 30 carried by the lever, a member adjustable to define the movement of the lever in one direction, and a stop member for defining the movement of the lever in the other direction. 35

In testimony whereof I have signed my name to this specification.

ALBERT P. HART.
